US00D959516S

(12) **United States Design Patent** (10) **Patent No.:** **US D959,516 S**
Mustafa et al. (45) **Date of Patent:** **** Aug. 2, 2022**

(54) **COMPRESSION FITTING**

(71) Applicant: **Applied Materials, Inc.**, Santa Clara, CA (US)

(72) Inventors: **Muhammad Mustafa**, Milpitas, CA (US); **Muhammad M. Rasheed**, San Jose, CA (US)

(73) Assignee: **APPLIED MATERIALS, INC.**, Santa Clara, CA (US)

(**) Term: **15 Years**

(21) Appl. No.: **29/739,304**

(22) Filed: **Jun. 24, 2020**

Related U.S. Application Data

(63) Continuation of application No. 16/750,595, filed on Jan. 23, 2020.

(74) *Attorney, Agent, or Firm* — Servilla Whitney LLC

(57) **CLAIM**

The ornamental design for a compression fitting, substantially as shown and described.

DESCRIPTION

FIG. 1 is a top-front isometric view of a compression fitting with additional disclaimed environment;

FIG. 2 is a front view of the compression fitting of FIG. 1; FIG. 3 is a rear view of the compression fitting of FIG. 1; FIG. 4 is a left side view of the compression fitting of FIG. 1;

FIG. 5 is a right side view of the compression fitting of FIG. 1;

FIG. 6 is a top view of the compression fitting of FIG. 1; FIG. 7 is a bottom view of the compression fitting of FIG. 1; and,

FIG. 8 is an exploded view of the compression fitting of FIG. 1.

Portions of the article shown in dotted lines form no part of the claimed design.

1 Claim, 5 Drawing Sheets
